UNITED STATES PATENT OFFICE.

EDWARD F. O'BRIEN, OF WEST SOMERVILLE, MASSACHUSETTS, ASSIGNOR TO J. RUSH GREEN, OF SOMERVILLE, MASSACHUSETTS.

SHOE-RACK.

1,058,194.

Specification of Letters Patent.

Patented Apr. 8, 1913.

Application filed May 20, 1912. Serial No. 698,375.

To all whom it may concern:

Be it known that I, EDWARD F. O'BRIEN, a citizen of the United States, residing at West Somerville, county of Middlesex, State of Massachusetts, have invented an Improvement in Shoe-Racks, of which the following description, in connection with the accompanying drawing, is a specification, like characters on the drawing representing like parts.

This invention relates to a rack for supporting or holding boots or shoes. Racks of this general type are extensively employed in shoe factories for holding the boots and shoes during the process of manufacture and for transporting them from one stage of the process of manufacture to another. In such manufacture it is desirable at times that the boots or shoes shall be supported with the sole upward, and at other times that they shall be supported with the sole downward, and transferred in either position to the next stage in the process of manufacture. It is important also that when supported in either position the boots or shoes shall not be easily subject to accidental displacement, and shall be so supported that they will be guarded from injury by contact with each other or by being rubbed against, jarred or hit. It is also essential that the boots or shoes shall be so supported that they may be readily placed in and removed from the rack in whichever position they are supported in the rack.

The object of this invention is to provide a single rack of such a construction that the boots or shoes may be held in either position, as required, that is with the sole upward or downward, and may be removed when in the one position and restored in the other position in the same place in the rack. This object the present invention secures while retaining the rack in snug and compact form.

The invention also provides a rack of simple and strong construction and one capable of withstanding the wear and tear of factory use.

An important feature of the invention resides in the construction enabling the boot or shoe to be held at one point in the rack in position, either with its sole downward or with its sole upward.

The invention will appear more fully from the accompanying description and drawings

and will be particularly pointed out in the claims.

The drawings illustrate a preferred form of racks embodying the invention, but it is to be understood that the invention is not restricted to any particular mechanical construction nor to be limited other than as required by the claims.

In the drawings—Figure 1 is an end elevation of a rack of the alternating type. Fig. 2 is a front elevation of the end portion of a rack of either the single or double type. Fig. 3 is a top plan view of a portion of a rack showing the arrangement of the supporting members and toe supporting bar. Fig. 4 is an end elevation partially in cross-section of a portion of the double type of rack to show the arrangement of the supporting members and toe supporting bar.

The rack comprises a frame which may be of any suitable material or construction. It is herein shown as having a base made up of front bars 1 and end bars 2, mounted upon casters 3. The ends of the frame are shown as vertical uprights 4 connected by cross bars 5, and these ends are shown as braced from the base by diagonal braces 6.

The present invention provides a plurality of horizontally arranged toe supporting bars 7 suitably mounted in the frame and preferably extending longitudinally thereof, that is from end to end. In the constructions illustrated these supporting bars are of general T shape with the heads resting upon and secured to the cross bars 5, the heads being wedge shaped so that the web portion of the supporting bars 7 is inclined to the vertical. These supporting bars may be arranged in different ways according to the size and style of the rack. In Fig. 1 the horizontal supporting bars 7 have a staggered or alternating relation, thus enabling, as will be seen, the boots and shoes supported thereby to form alternating rows on each face or side of the rack. As shown in Fig. 4, these horizontal supporting bars 7 are arranged parallel to each other and centrally of the rack, forming what is termed a "double rack," and other arrangements may be employed if desired. When the shoes are in position with the sole upward, the horizontal supporting bars 7 serve as the support for the toe end of the boot or shoe. Preferably also and in the forms herein illustrated the supporting arms and

100 105 110

members to be described are secured to and supported from these horizontal supporting bars.

A plurality of arms are mounted in the frame in horizontal rows and inclined upwardly toward their free ends. Preferably, as stated, these arms are secured to and project from the horizontal supporting bars 7. Four of such arms are shown in plan view 10 in Fig. 3. Each arm 8 is substantially flat upon its upper surface, presents concaved side edges 9, and has an enlarged head 10, and is provided centrally and longitudinally at its upper surface with suitable shoe separating means such as the rib 11. These arms 15 may be made of suitable material which will properly support the boot or shoe without injury thereto, and for that purpose may be made of wood. The opposing and adjacent 20 halves of these arms constitute pairs of boot or shoe supporting members. When it is desired to place the boot or shoe in position, sole downward, as at 12 or 13, the boot or shoe is placed on these supporting members 25 and rests firmly in place and against the horizontal supporting bars 7 and is separated from adjacent boots or shoes by the separating means or ribs 11. When it is 30 desired to place the boot or shoe in position with the sole upward as at 14, the upper is slipped in between the adjacent edges of the supporting members and the toe is placed upon the horizontal supporting bars 7, the concaved edges of the supporting members 35 receiving the upper and holding the boot or shoe in position. It will thus be seen that a boot or shoe may be put in the same place with either the sole up or the sole down as required and without changing its position 40 in the rack, and will in either position be held securely in place and separate from the other boots or shoes. The members of the horizontal rows of arms are preferably staggered vertical, that is the members of the one 45 row alternate in position with the members of the row above and the row below, as

shown in Fig. 2, thus enabling the horizontal rows to be brought closer together.

Having fully described my invention, what I claim as new and desire to secure by Letters Patent is:—

1. A rack for holding boots or shoes comprising a frame, a plurality of arms mounted in said frame in horizontal rows and inclined upwardly toward their free ends, 55 each arm presenting a substantially flat upper surface, concaved side edges and an enlarged head, and provided centrally and longitudinally on said upper surface with separating means, whereby boots or shoes 60 may be supported and held separately, either sole upward or sole downward, in the same position in the rack.

2. A rack for holding boots or shoes comprising a frame, a plurality of horizontal 65 supporting bars, a plurality of arms projecting outwardly from and inclined upwardly from said bars, each arm presenting a substantially flat upper surface, concaved side edges, and an enlarged head, and provided centrally and longitudinally on said 70 upper surface with a rib, whereby boots or shoes may be supported and held separately, either sole upward or sole downward, in the same position in the rack. 75

3. A rack for holding boots or shoes comprising a frame, a plurality of pairs of boot or shoe supporting members, each pair of the said members having means to receive between them and hold separate from 80 other boots or shoes a boot or shoe, with the sole upward and to receive upon them and hold separate from other boots or shoes a boot or shoe with the sole downward.

In testimony whereof, I have signed my 85 name to this specification, in the presence of two subscribing witnesses.

EDWARD F. O'BRIEN.
